UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP HAVING AS TRUSTEES J. W. TOWNE, F. B. TOWNE, E. S. TOWNE, J. M. TOWNE, AND F. W. WILSON.

LOOSE-LEAF BINDER.

1,270,975.

Specification of Letters Patent.

Patented July 2, 1918.

Application filed July 17, 1917. Serial No. 181,061.

To all whom it may concern:

Be it known that I, JOHN SCHADE, a citizen of the United States, residing at Holyoke, Hampden county, State of Massachusetts, have invented certain new and useful Improvements in Loose-Leaf Binders; and I do declare the following to be a full, clear, and exact description of the invention, such as will enable others skilled in the art to 10 which it appertains to make and use the same.

This invention relates to certain new and useful improvements in a loose leaf binder and pertains more particularly to a hinge 15 construction for the covers of loose leaf transfer binders.

The primary object resides in an improved hinge knuckle or socket and the manner of mounting the same on the tubular bar or 20 casing.

The invention further resides in the features of construction and the arrangements of parts hereinafter described and claimed, reference being had to the accompanying 25 drawing wherein,

Figure 1 is a fragmentary top plan of a loose leaf binder having the present invention incorporated therein;

Fig. 2 is a transverse section on line 2—2 30 of Fig. 1 illustrating more clearly the present embodiment of the invention;

Fig. 3 is a detailed elevation of a hinge knuckle, *per se*; and

Fig. 4 is a sectional view thereof taken 35 on line 4—4 of Fig. 3.

In detail, the drawing discloses a tubular casing or bar 1 and a cover member 2 of a loose leaf binder which are hingedly connected by the following construction.

40 The tubular bar 1 is preferably formed by bending a sheet of metal longitudinally to form upper and lower sides with its free edges constituting the inner end wall, said free edges being slightly spaced to receive 45 therebetween the neck portions 3 of the hinge knuckles or pintle socket members 4.

Each pintle socket member is conveniently formed from a strip of metal bent midway of its ends to form a socket or knuckle part 50 5 from which the sides of the strip are extended to provide a comparatively reduced neck 3, said sides being then separated and extended in parallel relation to form the

cheek pieces 6. Each cheek piece is formed with an outwardly extending tubular socket 55 or eyelet 7.

The tubular bar is formed in its upper and lower sides and at regular intervals with registering apertures for the reception of the eyelets 7 which latter are then expanded to secure the cheek pieces 6 to the bar. This provides a simple and efficient means for securing the socket members to the bar and at the same time affords a reinforcement for the latter. The neck 3 being disposed in the slot of the bar serves as a sustaining spacer for the free edges of the strip which define the slot.

The other hinge section 2 is preferably made of steel secured to a cover made of 70 binders' board and provided with the sockets 8 which register between the casing or bar sockets 4 to receive therewith the hinge pintle 9 and thus complete the hinge connection. It is obvious that any number of 75 hinge knuckles may be employed, and while the invention is especially adapted for loose leaf transfer binders, it is also capable of use in a top lock binder or in other structures embodying a hinge connection.

The particular securing of the cheek pieces, while not interfering with the usual internal working parts of the casing, prevents the spreading or expansion of the tubular casing, and the neck portions, being 85 interposed between the free edges of the casing, prevent collapsing of the latter. Thus, the casing is stiffened and reinforced throughout its length. Consequently, the casing may be constructed simply by bending over a piece of sheet metal, and thereby obviating the necessity of employing drawn or seamless tubing.

While I illustrate the integrally formed eyelet struck up at 7, as shown in Fig. 4, 95 still it is apparent that this feature could be varied by substituting therefor a separate rivet or eyelet, or I could spot weld, braze, or solder the cheek pieces 6 to the bar 1 and yet retain, in other respects, the features of 100 the general construction as described in my invention.

What is claimed is:—

1. In a loose leaf binder, a casing constructed by bending over a sheet of metal to 105 form a tubular casing having its free edges

- defining a slot, said casing having spaced sets of registering perforations, and a plurality of hinge knuckles each formed of a strip of metal bent transversely to form a 5 knuckle part and then extended to provide a neck portion for disposal in the casing slot to reinforce the casing against collapsing, the ends of said strip being extended from the neck portion in spaced relation to provide 10 cheek pieces, each of which is formed with an outwardly extending eyelet, the oppositely extending eyelets of each of the cheek pieces engaging in a set of registering perforations of the casing and expanded to 15 secure the cheek pieces to the casing.
2. In a hinge for loose leaf binders, a casing having a pair of registering perforations, and a slot, and a hinge knuckle comprising a pintle receiving knuckle part, a 20 neck part for disposal in the casing slot, and spaced cheek pieces each having an outwardly projecting eyelet engaged on one of the registering perforations of the casing and expanded for securing the cheek piece 25 in the latter.
3. In a loose leaf binder, a casing having registering openings, and a hinge knuckle

having a support formed with oppositely extending eyelets engaging in the openings of the casing and expanded for securing the 30 knuckle to the latter.

4. In a loose leaf binder, a casing having registering openings, and a hinge knuckle having a part extending within the casing and formed with rivets passing through the 35 casing openings for securing the knuckle to the casing.

5. In a loose leaf binder, a casing having registering openings, a hinge knuckle having spaced cheek pieces extending within 40 the casing, and means extending through the openings of the casing for securing the cheek pieces to the latter.

6. In a loose leaf transfer binder in combination, an oval metal tube, a hinge support having spaced parallel faces engaging the inside of said tube and means for securing the same to the tube.

In testimony whereof I affix my signature.

JOHN SCHADE.
